CONDENSING COVER FOR A SAUCE PAN OR THE LIKE

Robert E. Widdows, 1941 Larkspur Drive,
Fort Collins, Colo. 80521

Filed Feb. 1, 1973, Ser. No. 328,838

Term of patent 14 years

Int. Cl. D7—02

U.S. Cl. D7—131

Fig. 1

Fig. 3

FIG. 1 is a perspective view of a condensing cover for a sauce pan or the like embodying my new design;

FIG. 2 is a side elevational view thereof; and

FIG. 3 is a cross-sectional view taken centrally through FIG. 2.

I claim:

The ornamental design for a condensing cover for a sauce pan or the like, as shown.
